UNITED STATES PATENT OFFICE.

VICTOR H. JENNINGS, OF WORCESTER, MASSACHUSETTS, ASSIGNOR TO MILLS WOVEN CARTRIDGE BELT COMPANY, OF WORCESTER, MASSACHUSETTS, A CORPORATION OF MASSACHUSETTS.

WOVEN TUBE AND METHOD OF WEAVING THE SAME.

1,137,405.

Specification of Letters Patent. Patented Apr. 27, 1915.

Application filed September 23, 1912. Serial No. 721,867.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Tubes and Methods of Weaving the Same, of which the following is a specification, reference being had therein to the accompanying drawings.

The invention consists in a tubular woven fabric having a plurality of sides meeting at angles, the corners being angularly defined in the weaving. Also, in a tubular 15 woven fabric having an opening extending transversely across manifold warp-spaces as well as longitudinally of the warps, with its lateral margins formed with selvages produced in the weaving. Also, in a tube woven 20 with an opening as aforesaid in one side thereof and with a narrow longitudinal slit in another side, and adapted to constitute a blank for a vehicle-lamp cover. Also in a novel method of weaving.

The features of the invention are illustrated in the drawings, in which latter—

Figure 1 is an isometric view of a woven tube embodying the said features. Fig. 2 is a view showing the slotted side of the 30 said tube. Fig. 3 is a diagrammatic representation of the method of weaving the plain portion of the tube, and the general fabric-structure thereof. Fig. 4 is a similar representation of the portion of the tube containing 35 the transverse opening and the narrow longitudinal slit, and the method of weaving the same. Fig. 5 is a similar representation illustrating a fabric woven without the said narrow longitudinal slit.

Having reference to the drawings—the tube represented in Fig. 1 has four sides meeting at right-angles. In the present instance the sides 1 and 2 are of continuous fabric, without openings or slits. Side 3 is 45 formed with the wide transverse opening or window 3^a having the opposite selvage lateral margins, 3^b, 3^b, which are finished in the weaving, and side 4 is formed with the narrow longitudinal slit 4^a having the margins 50 thereof selvaged, finished in the weaving.

Figs. 3, 4, and 5 illustrate the general manner of weaving the rectangular tubular web or fabric of Fig. 1, namely in a flattened state and in four superimposed plies at each

side of the longitudinal middle of said web 55 or fabric, all joined together in the weaving. The top and bottom plies *a* and *b* in said figures correspond to the sides 1 and 2 of Fig. 1, and in the web or fabric as woven in a loom the said plies are extended transversely and flat to the full width of the said sides. The two narrow intermediate plies *c*, *d*, at the right in Figs. 3 and 4 constitute the side 3 in a state doubled upon itself transversely and lying between the plies 60 *a* and *b*; and the two narrow intermediate plies *e* and *f* at the left in said figures constitute the side 4, similarly doubled upon itself. The warp-threads are marked *g*, *g*, in Figs. 3, 4, and 5.

In weaving a plain tube, as in the lower portion of the tubular fabric or article of Fig. 1 below the opening or window 3^a and slit 4^a, the threads are interwoven substantially as in Fig. 3. In the latter a single 75 weft-thread *h* is employed. Starting at the left in Fig. 3, the first pick of the weft-thread *h* extends from the extreme left to the extreme right through the top ply *a*. The second pick extends from the extreme 80 right through the upper right-hand intermediate ply *c* to the transversely-intermediate point *c*. The third pick extends from point *c*' from left to right through the lower right-hand intermediate ply *d* to the extreme 85 right. The fourth pick extends through the bottom ply *b* from the extreme right to the extreme left. The fifth pick extends from left to right through the lower intermediate ply *f* to the transversely-intermediate point *f*'. The sixth pick extends from right to left through the upper left-hand intermediate ply *e* to the extreme left. The 90 seventh pick extends from the extreme left to the extreme right through a second shed 95 in the top ply *a*, and in like manner the eighth, ninth, tenth, eleventh, and twelfth picks extend in the same directions respectively as the second to sixth picks, through the remaining successive plies, but through 100 a second shed in every such ply. One round or repeat of the weave is completed by the return of the weft to the starting side in Fig. 3, after completing the pick from right to left through the left-hand upper intermediate ply *e*. In consequence of the outer portions of the right-hand intermediate plies *c*, *d*, being joined in the weaving to the 105

- right hand portions of the top and bottom plies a , b , and in consequence of the inner portions of such intermediate plies being joined together in the weaving, the said 5 plies c , d , will together constitute one side of the tube of Fig. 1 when straightened out in line transversely with each other by moving the sides that are constituted by the top and bottom plies a , b , apart from each other.
- 10 The fourth side of the tube will be constituted by the left-hand intermediate plies e , f , when similarly straightened out in line transversely with each other. The result of weaving the web in superimposed plies 15 united by the weft-threads along the lines of junction of the plies a , b , with the plies c , d , and e , f , is that folds or bends and creases are produced in the web, serving to define the corners of the tube, which retain 20 normally an angular set.
- The opening or window 3^a is produced, as shown at the right in Figs. 4 and 5, by floating the warp-threads g' , g'' , etc., of the inner portions of the two intermediate plies 25 c , d , which make one folded-in side of the tube, and interweaving the weft with only the warp-threads of the outer portions of such intermediate plies. The narrow woven portions c^2 , d^2 , thus produced are formed 30 with selvages, and are left unconnected with each other by causing the weft in the case of each thereof to pass inwardly within the same and also return outwardly therein without crossing over to the other thereof.
- 35 The narrow slit 4^a is produced by forming the inner portions of the intermediate plies e , f , which together constitute the side containing such slit, with distinct edges, unconnected with each other throughout the 40 length of the slit. The selvages at such slit are produced by causing the weft of each such ply to extend inwardly through the ply and then return outwardly without crossing over to the other ply.
- 45 Fig. 4 represents one manner in which the portion of the tube containing the opening or window and slit may be woven with the aid of two shuttles. Thus, in the case of one weft-thread, h' , the first pick thereof, 50 starting at the extreme left, extends to the extreme right through the top ply a ; the second pick extends from right to left through the narrow intermediate portion c^2 ; the third pick returns from left to right 55 through such portion; the fourth pick extends from extreme right to extreme left through the top ply a ; the fifth pick extends from left to right through intermediate ply e ; and the sixth pick extends from right to 60 left through said intermediate ply e back to the starting point. The other weft-thread, h'' , starting at the extreme left, extends from left to the extreme right through ply b ; the second pick extends from right to left 65 through the narrow portion d^2 ; the third

pick extends from left to right through said narrow portion d^2 ; the fourth pick extends from extreme right to extreme left through ply b ; the fifth pick extends from left to right through lower intermediate ply f to 70 the inner edge of the latter; and the sixth pick extends from right to left through said lower intermediate ply f back to the starting point.

Fig. 5 illustrates the method of weaving, 75 and substantially the fabric structure, in case the narrow slit 4^a is omitted. Starting at the extreme left, the first pick of weft extends through ply a to the extreme right; the second pick of weft extends from right 80 to left through the narrow portion c^2 ; the third pick returns from left to right through the said narrow portion c^2 ; the fourth pick returns from extreme right to extreme left through ply a ; the fifth pick extends from 85 extreme left toward the right through upper intermediate ply e ; the sixth pick extends from right to left through lower intermediate ply f ; the seventh pick extends from extreme left to extreme right through ply b ; 90 the eighth pick extends from right to left through narrow intermediate portion d^2 ; the ninth pick extends from left to right through said portion d^2 ; the tenth pick extends from extreme right to extreme left 95 through ply b ; the eleventh pick extends from left to right through lower intermediate ply f ; and the twelfth pick extends from right to left through upper intermediate ply e back to the starting point. When 100 the opening or window 3^a has been given the desired measurement in the direction of the length of the tube, the weft is interwoven again, as in Fig. 3, with the warp-threads which have been floated in producing the 105 said opening or window. Thereby solid or continuous fabric will be produced contiguous to the opening or window. Above the level of the top of the opening or window, the slit 4^a is continued by a method of 110 weaving similar to that illustrated in Fig. 5 in connection with the opening or window. The weaving of the tube is continued by repetition of the plain tubular portion, followed by portions containing an opening or 115 window and slit, and so on.

The blank produced in manner herein described and shown in Fig. 1 is more particularly adapted to be utilized in the production of a cover for a vehicle-lamp. The upper and lower ends of the said blank will be cut, shaped, and stitched or otherwise treated to form a top or hood and bottom; or a top or hood and bottom will otherwise be provided. The slit 4^a is intended to receive the supporting arm of a lamp, and to permit the cover to be drawn up around the lamp. The opening or window 3^a is designed to receive a transparent pane, as of celluloid, or analogous material, to permit 125 130 135

the light of the lamp to issue for purposes of illumination in the required direction. The floating or loose warp-threads crossing the said opening or window will be trimmed off.

5 Suitable fastenings will be provided for securing the cover in closed condition about the lamp. The width of slit 4^a may be increased by floating some of the innermost warp-threads of the intermediate plies *e*, *f*, 10 in the weaving as in the case of warp *g*, *g'*, for the required length of slit, and subsequently trimming them off.

What is claimed as the invention is:—

1. A tubular woven fabric having a plurality of sides meeting at angles, with the corners angularly defined in the weaving and with each of said sides composed of its individual set of warp threads.

2. A tubular woven fabric having woven 20 in one side of the tube an opening or window extending transversely across manifold warp-spaces as well as longitudinally of the warps, with its lateral margins formed with selvages produced in the weaving, the intervening warp-threads floated from top to bottom of the opening or window, and weft-threads omitted from said top to said bottom.

3. A tubular woven fabric having in one 30 side thereof an opening or window extending transversely across manifold warp-spaces as well as longitudinally of the warps, with its lateral margins formed with selvages produced in the weaving, and with a longitudinal selvaged slit in another side thereof.

4. A tubular woven fabric having a plurality of sides greater than two meeting at angles, the corners defined in the weaving, 40 and having woven in one of the said sides an opening or window extending transversely across manifold warp-spaces as well as longitudinally of the warps, with its lateral margins formed with selvages produced in the weaving.

5. A tubular woven fabric having a plurality of sides meeting at angles, the corners defined in the weaving, and having woven in one of the said sides an opening or window 50 extending transversely across manifold warp-spaces as well as longitudinally of the warps, and also having woven in another of the said sides a narrow longitudinal slit,

said opening or window and said slit having lateral margins formed with selvages produced in the weaving.

6. The method of producing a rectangular woven tube with the corners thereof defined in the weaving, which consists in weaving two opposite sides thereof in flat extended planes, one above the other, and weaving two connecting sides in folded-in state opposite each other between said flat extended plies, with the outer portions of each folded side joined in the weaving to the contiguous margins of said plies.

7. The method of weaving which consists in weaving two plies of cloth, one above the other, weaving a connecting portion as a flat inward fold between the said plies, with the outer margins of the folded connecting portion joined in the weaving to the contiguous margins of the said plies, and producing an opening or window in the said connecting portion by floating the warps of the latter at and adjacent the bend or bight thereof, forming selvages on the lateral margins of the opening or window by returning the weft upon itself within the same plane of the fold after each pick to the inner margin thereof.

8. The method of producing a rectangular woven tube having the corners at its angles defined in the weaving, and of forming an opening or window in a side of said tube, 85 which consists in weaving opposite sides in flat extended plies, one above the other, weaving each connecting side as a flat inward fold between such extended plies, with the outer portions of the in-folded side joined in the weaving to the contiguous margins of the said plies, floating the warps of the two planes of an in-folded side at and adjacent the fold, to form the opening or window, and forming selvages on the lateral 95 margins of the opening or window by returning the weft upon itself within the same plane of said fold after each pick to the inner margin thereof.

In testimony whereof I affix my signature 100 in presence of two witnesses.

VICTOR H. JENNINGS.
